ELECTRICAL FIXTURE

Marshall S. Wideroe, Northbrook, Ill., assignor to
Benjamin Electric Mfg. Company, Des Plaines,
Ill., a corporation of Illinois

Application December 22, 1938, Serial No. 247,240

4 Claims. (Cl. 240—78)

This invention relates to an electrical fixture.

One of the objects of my invention is the provision of a fixture which may be readily detached from a permanently located electrical outlet such as might be positioned in a wall or ceiling.

A further object of this invention is the provision of improved means for installing lighting fixtures in a suitable outlet positioned in a ceiling which may be readily detached therefrom.

A further object of this invention is to provide improved means whereby a lighting fixture may be readily detached from its position in a ceiling without the necessity of separately disconnecting the wires extending into the fixture.

A further object of this invention is to provide an improved means whereby a reflector may be secured to an enameled reflector bowl.

Further and additional objects will appear from the following description, the accompanying drawings, and the appended claims.

In the drawings,

Figure 1 is a sectional view of a lighting fixture constructed in accordance with one embodiment of this invention secured to a ceiling;

Fig. 2 is a partial side view of the construction shown in Fig. 1 in which the hood is raised and a tool for disconnecting the lighting fixture from the stationary unit is shown engaged with the detachable unit, the dotted lines indicating the direction in which the detachable unit may be pivoted in order to permit disengagement from the stationary unit;

Fig. 3 is a side view of the stationary unit of Fig. 1 showing the electrical contacts;

Fig. 4 is a bottom plan view of the structure shown in Fig. 3;

Fig. 5 is a side view of the upper portion of the detachable unit adaptable to be mounted on the stationary unit shown in Fig. 3;

Fig. 6 is a top plan view of the portion of the detachable unit shown in Fig. 5;

Fig. 7 is a partial perspective view of a tool that may be employed for detaching an electrical fixture constructed in accordance with this invention.

Fig. 8 is a perspective view of a nut having vertically extending members adaptable to engage a strap to which it may be secured; and

Fig. 9 is a perspective view of a strap to which is secured the nut shown in Fig. 8, whereby a hole in the strap registers with the threaded hole of the nut.

This invention contemplates the provision of an electrical fixture which may be readily detached from position in a wall or ceiling. It com-

prises a stationary unit comprising wiring terminals and receptacle contacts, which unit may be firmly secured in position in the ceiling and to which may be secured a detachable unit. The detachable unit which may comprise a lamp socket and reflector is pivotally mounted on the stationary unit in such a manner that the fixture will depend directly therefrom. The detachable unit may be swung out of alignment with the stationary unit and the whole detachable unit, including the socket, light bulb, and reflector, may then be lifted free of the stationary unit. Electrical contacts are provided in the stationary and detachable units so that contact will be made when the fixture hangs in normal position but will be broken when the detachable unit is pivoted out of alignment and the detachable unit is disengaged from the stationary unit.

This invention further contemplates the provision of an electrical fixture having an enameled bowl portion and a reflector which may be secured together in a new and improved manner.

For a more complete understanding of this invention, specific reference will now be had to the drawings. As shown in Fig. 1, a lighting fixture may be suspended from an outlet box 10 by means of suitable connections including the wire conduit 11. The detachable unit may comprise a suitable inverted dished reflector 12, an enameled bowl 13, a lamp socket 14, and a mechanical connector sleeve 15 in which the socket 14 is mounted and to which the reflector and bowl are secured by suitable straps 16. The connector sleeve 15 is pivotally suspended at one end by two oppositely disposed inwardly projecting members 17 secured adjacent its upper end, which are detachably engageable in two notches 18 in the casing 19 of the stationary unit 20. The stationary unit 20 is secured to the end of the conduit 11 by means of a bracket 21 which is secured to the stationary member 20 by means of screws 22 extending therethrough. The bracket 21 is secured to a strap 23 by means of bolts 24. The strap 23 embraces the end of the conduit 11 and is held in position by means of a bolt 25 which extends through the bracket 21, the conduit 11, and the strap 23. The stationary unit 20 is thus firmly secured to the lower end of the conduit 11.

The stationary unit 20 may comprise a wiring and contact base 26 of any suitable insulating material and a suitable metallic casing 19 placed over the upper portion of the base 26 in order to protect it. The conduit 11 extends through the casing 19 into the base 26 in order to provide

a passage for wires (not shown) extending through the conduit 11 to the wiring terminals for electrical contact supports 27 positioned within the insulating base 26. The electrical contact supports 27 are secured within the base 26 by means of suitable screws 28 extending through the base and threaded directly into the contact supports 27. Binding screws 29 may be threaded into the contact supports 27 in order to permit the wires (not shown), extending from the conduit 11, to be electrically connected to the contact supports. At the extreme ends of the contact supports 27 may be secured suitable contact clips 30 which are positioned within recesses 31 of the base 26 and are adapted to engage registering contacting blades 32 which are mounted on the insulating base 34 of the socket 14 positioned within the connector sleeve 15 of the detachable unit. The contact blades 32 are also electrically connected with the socket contacts. Suitable V-shaped notches 33 are provided adjacent the recesses 31 in order to direct the blades 32 into the recesses 31 and between the spring contact clips 30.

The detachable unit comprises the hollow cylindrical shell or sleeve 15 within which may be positioned the lamp socket 14 carrying contact blades 32. The contact blades 32 extend above the upper portion of the lamp socket from a suitable insulating base 34 to which the vertically extending blades 32 are secured by means of screws 35 and 36. One of the screws 35 electrically connects one of the contacts 32 with the shell contact of the lamp socket 14. The insulating base 34 is secured to the connector sleeve 15 by means of suitable ears 37 extending inwardly from the side walls of the sleeve. The ears 37 and the base 34 may be secured together by suitable screws 38.

The shell contact of the socket 14 may be of any suitable construction and may be secured to the under side of the insulating base 34 by means of suitable screws 35, 36, and 39. One of the contacts 32 is electrically connected with the center contact of the socket by means of the screw 36. The connector sleeve 15 has oppositely disposed ears 40 extending from its upper edges, to which may be secured the two inwardly projecting members 17. The members 17 may be riveted or welded to the ears 40 and are adapted to rest within the oppositely disposed notches or grooves 18 in the upper portion of the casing 19. The detachable member is pivotally mounted on the stationary member by means of the members 17 resting in the grooves 18. The blades 32 within the connector sleeve 15 are positioned so that they will engage the contact clips 30 within the stationary member 20 when the detachable member is suspended from the pivots 17 within the groove 18.

A vertically extending hood 41 which is slidably mounted on the conduit 11 may be positioned to cover the stationary unit 20 and the connector sleeve 15. The hood 41 has shoulder portions 42 adjacent the upper end thereof which rest upon the casing 19 and thereby support the hood. The hood 41 may be moved vertically along the conduit 11 as indicated in Fig. 2 in order to permit the detachable unit to be pivotally swung out of alignment with the conduit 11 and the stationary unit 20. A means may be provided for holding the hood 41 in the raised position which comprises suitable ears 43 positioned on the upper outside edges of the bracket 75

21, which secures the stationary member 20 to the conduit 11.

The lighting fixture, when connected and in use, is in the position indicated in Fig. 1. The hood 41 is down and the detachable connector 15 is housed thereby. In order to detach the lighting fixture from the conduit 11 and the stationary unit 20, the hood 41 is first raised and held in the raised position by resting a lower edge of the hood 41 on the bracket 21 inside of one of the ears 43. The entire detachable unit, including the reflector 12 and bowl 13, may then be swung on the pivot members 17 so that the contact blades 32 are disengaged from the clips 30 and are wholly removed from the recess 31 and the notch 33 in the stationary member 20. The whole detachable unit may then be lifted away from the stationary unit 20 by lifting upwardly, whereby the inwardly projecting pivot members 17 are removed from the grooves 18 in the upper portion of the casing 26.

It is often desirable to remove and interchange fixtures of this type from ceilings which are not conveniently accessible except by means of step ladders or suitable scaffolding. A lighting fixture mounted in accordance with this invention may be readily removed, however, by means of a suitable tool which may be fastened to the end of a long pole. The tool comprises 25 a bifurcated member 44 which may be secured to a pole 45 of any suitable length by means of brads or screws 46. Rubber sleeves 47 may be provided on each of the prongs 48 of the bifurcated member 44, if desired. The ends of the 30 prongs 48 are spread somewhat further apart than the portions of the prongs adjacent the base. Thus, the outwardly extending portion is adapted to engage the hood 41 for lifting it and the inside portion of the fork is adapted to engage the connector sleeve 15, whereby it may be tilted. Upwardly and inwardly extending members 49 may be provided in the prongs which are adapted to abut outwardly and downwardly extending tongues 50 positioned on opposite sides 35 of the connector sleeve 15 and adjacent the central portion thereof.

In removing the lighting fixture with the tool, the hood 41 is first lifted into the position shown in Fig. 2 by means of the fork in the tool. The 40 rubber sleeves 47 are provided in order to prevent the hood 41 from becoming scratched and also to provide a frictional engagement of the tool with the hood so that the latter may be readily lifted into position. The tool then may be positioned so that the prongs 48 extend around the connector sleeve 15 and the base of the prongs 48 bears against the sides of the connector sleeve 15. The tool is raised so that the upwardly and inwardly extending members 49 abut the sides 45 of the tongues 50 on the connector sleeve 15 in order to lock the tool 44 in position. Movement of the handle 45 of the tool downwardly in a vertical direction in the pivotal plane of the detachable member will cause a portion of the tool to bear down against the outside rim of the bowl portion 13. The whole detachable portion of the fixture is thereby pivoted to the left as shown in Fig. 2 and the contact blades 32 become disengaged from the contact clips 30 in the stationary unit 20. When the fixture has been tilted to such an extent that sufficient clearance is provided, the detachable unit may be readily lifted free from the grooves 18 in the stationary unit casing 19 and the whole detachable portion may be brought down from the ceiling on the end 50

of the pole 45. For attaching the detachable unit to the stationary unit, the reverse procedure is employed.

A particular feature of this invention is to provide a means for securing the reflector to the bowl portion of the lighting fixture. It is desirable in many instances to provide a reflector of polished aluminum or stainless steel in a lighting fixture which is to be attached to an enameled metal bowl. It has not been satisfactory to secure these elements together simply by means of bolts threaded directly into the enameled portion, since it is impractical to preserve threads during the enameling operation and it is difficult subsequently to thread the enameled portions without chipping the enamel. It has consequently become desirable to provide a means whereby the reflector may be bolted or otherwise threadably secured to the enameled bowl in any desired position.

In accordance with one embodiment of this feature of this invention, as is shown in Figs. 1, 8, and 9, a strap 51 may be welded to the bowl portion adjacent the point where it is desired to attach the reflector portion previous to the enameling operation. The strap 51 may be U-shaped, having a hole 52 positioned in its apex adapted to register with a corresponding hole in the reflector.

After the bowl and strap have been welded and enameled, a nut, shown in Fig. 8, may be firmly engaged to the strap 51. The nut 53 has a threaded hole 54 which is adapted to register with the hole 52 in the strap 51. The nut 53 may be provided with a plurality of outwardly extending members 55 which are adaptable to embrace the strap 51, as shown in Fig. 9. The upwardly extending members 55 may have outwardly extending portions 56 which are adaptable to fit the contour of the hole 52 when the members 55 are bent around the strap and the nut 53 is clamped in place.

Thus, a nut has been provided which may be separately but firmly attached to an enameled strap. This construction is particularly desirable, since the reflector and bowl may be secured directly by means of a bolt 57 without the necessity of providing threaded portions in the enameled bowl or strap. The construction also renders it unnecessary that access be had to the nut to hold it in place while the bolt is screwed thereinto, since the nut is firmly secured to the strap as if it were an integral part thereof.

While a particular embodiment of this invention is shown above, it will be understood, of course, that the invention is not to be limited thereto since many modifications may be made, and it is contemplated, therefore, to cover any such modifications as fall within the true spirit and scope of this invention as defined by the appended claims.

I claim:

1. In a readily serviceable lighting fixture the combination with a permanent fixture supporting structure and a quickly detachable lighting unit of means for establishing fixture supporting and current conducting cooperation therebetween comprising a terminal portion on said permanent fixture supporting structure having supporting slots accessible from the top, and laterally accessible contact slots having concealed electrical

contacts therein, said quickly detachable lighting unit having an upper portion with supporting fingers for engagement with the supporting slots and electrical contacts for engagement with the concealed electrical contacts through said laterally accessible slots whereby interfitting the supporting fingers into the slots and movement of the lighting unit into alignment with the fixture supporting structure causes the electrical contacts on the unit to enter the slots and engage the contacts on the terminal portion of the fixture supporting structure.

2. In a readily serviceable lighting fixture the combination with a permanent fixture supporting structure and a quickly detachable lighting unit of means for establishing fixture supporting and current conducting cooperation therebetween comprising a terminal portion on said permanent fixture supporting structure having supporting slots accessible from the top, and laterally accessible contact slots having concealed electrical contacts therein, said quickly detachable lighting unit having an upper portion with supporting fingers for engagement with the supporting slots and electrical contacts for engagement with the concealed electrical contacts through said laterally accessible slots whereby interfitting the supporting fingers into the slots and movement of the lighting unit into alignment with the fixture supporting structure causes the electrical contacts on the unit to enter the slots and engage the contacts on the terminal portion of the fixture supporting structure, and locking means to retain said parts in operating relation.

3. An electric lighting fixture comprising an elevated unit and a suspended unit, said elevated unit having quick detachable contacts and quick detachable hook pivot means, said suspended unit comprising quick detachable contacts for engagement and disengagement with respect to the contacts on the elevated unit, and quick detachable hook pivot means, said hook pivot means being engageable with the hook pivot means on the elevated unit by lateral and downward movement of said suspended unit and disengageable by lateral and upward movement, said elevated unit and suspended unit having cooperating abutments brought into vertical alignment by lateral movement of the suspended unit, and releasable locking means for holding the abutments in vertical alignment comprising a sleeve slidable on the elevated unit movable into and out of engagement with the suspended unit.

4. An electric lighting fixture comprising an elevated unit and a suspended unit, said elevated unit having quick detachable contacts and quick detachable hook pivot means, said suspended unit comprising quick detachable contacts for engagement and disengagement with respect to the contacts on the elevated unit, and quick detachable hook pivot means, said hook pivot means being engageable with the hook pivot means on the elevated unit by lateral and downward movement of said suspended unit and disengageable by lateral and upward movement, the contacts on the elevated unit being located in laterally-opening recesses and the contacts on the suspended unit being engageable with the contacts on the elevated unit through said lateral recesses.
